UNITED STATES PATENT OFFICE.

EDWARD T. LASKEWITZ, OF LYNNVILLE, IOWA, ASSIGNOR OF ONE-HALF TO LEWIS C. SCHNELL, OF KELLOGG, IOWA.

39 ~~mean time three, that will be made of iron and steel, or other suitable material, and will be of a size to receive or hold, when held in a horizontal position, a weight of 12 lbs. and a 50 horizontal pull to draw the two rails together, and to hold the same in position, and will be of a length of 12 ft. and 12 in. in width.~~

51 ~~1,294,857. Patented May 1, 1917.~~

52 ~~Specification of Letters Patent. Application filed June 26, 1916. Serial No. 105,862.~~

To all whom it may concern:

Be it known that I, EDWARD T. LASKEWITZ, a citizen of the United States, and resident of Lynnville, in the county of Jasper 55 and State of Iowa, have invented a certain new and useful Rail-Joint, of which the following is a specification.

The object of my invention is to provide a rail joint of simple, durable and inexpensive 60 construction, adapted to lock the ends of 10 two rails together without the use of fish plates ordinarily used.

A further object is to provide such a rail joint so arranged as to allow some longitudinal 65 play of the rails with relation to a tie on which the joint is supported and allow for expansion and contraction.

My invention consists in the construction, arrangement and combination of the various 70 parts of the device whereby the objects contemplated are attained as hereinafter more fully set forth, pointed out in my claims and illustrated in the accompanying drawings, in which:

25 Figure 1 shows a top or plan view of a rail joint embodying my invention.

Fig. 2 shows a side elevation of the same.

Fig. 3 shows a vertical, sectional view taken on the line 3—3 of Fig. 1.

30 Fig. 4, shows a perspective view of the end of one of the rails.

Fig. 5 shows a perspective view of the central joint member and

Fig. 6 shows a transverse, sectional view 35 taken on the line 6—6 of Fig. 3.

The ends of the rails are given a peculiar shape when used as a part of my improved joint.

In the accompanying drawings, I have 40 shown the rail members comprising a base 10, the web or shank 11 and the ball or tread portion 12.

The sides of the ball, at the end of the rail, are cut away leaving the portion 12^a of substantially the same thickness as the web 11, extending upwardly flush with the upper level of the ball of the rail.

45 The portion 12^a and the web 11 are provided with downwardly extending notches 50 13, between the end of the rail and the portion of the ball 12 which has not been cut away, as clearly shown in Fig. 4.

I provide a cradle or base comprising a flat bottom member 14, the upright side members 15 and upwardly and inwardly inclined lugs 16, at the upper edge of each end of the members 15.

The connecting member 17 is provided having the form of a section of a rail in which, at each end, is a slot 18 extending longitudinally into the member 17 and extending from the top to the bottom of the member 17.

The member 17 is provided on each side of its transverse central line with a vertical slot 19 extending from top to bottom.

The lower portions of the slots 19 are connected by a longitudinally arranged slot in the lower part of the member 17, as shown in Fig. 3.

Extending transversely through the central portion of the web of the member 17 is an opening 20. The web of the member 17 is of less height than the web of the rail, so that the base of the member 17 may rest 75 upon the upper surface of the base 10 of the rail when the parts are assembled.

In assembling my improved rail joint for use, the cradle is slipped on to the end of one of the rails, the ends of two rails are 80 then placed in alignment and adjacent to each other spaced apart a short distance and the joint member 17 is placed in position from above, the notches 13 receiving the portions of the joint member 17 between the 85 respective slots 19 thereof and the respective notches 18 thereof.

The parts are so arranged that the base of the member 17 will rest on the rail bases with the upper surface of the member 17 90 flush with the upper surfaces of the balls of the adjacent rails.

The notches 13 are of larger size longitudinally of the rails than are those portions of the member 17 which said slots receive, and 95 the slots 19 and notches 18 are of such length longitudinally of the rails as to permit some play of the rails longitudinally with relation to the joint member 17.

The cradle or base member is then moved 100 longitudinally of the rail until it rests beneath the joint member 17. It will be noted that the portions 15 are of sufficient height so that the base of the rail and the base of

the joint member 17 may be received between the plate 14 and the lugs 16, as shown in Figs. 1 and 6.

After the parts have been thus assembled 5 a pin 21 is driven into the opening 20.

The pin 21 is designed to fit so tightly that it will not jar loose.

It will be seen that as long as the pin 21 is assembled it is impossible for the cradle 10 to work longitudinally of the rails a sufficient distance to move away from the joint member 17, for the reason that the longitudinal movement of the cradle is limited by the engagement of the lugs 16 with the pin 21.

15 It will be seen that the rail ends are firmly locked together without the use of fish plates, and without the use of bolts and nuts.

There are only three removable parts of my joint, excepting the rails themselves.

20 The parts are so connected that there is not only a proper joint, but there will be less pounding of the wheels against the rails at the joint, for the reason that the upper surface of the rail ends and the upper surfaces 25 of the joint member 17 are held joined with each other by the plates 12^a and the lugs 16.

Sufficient play of the rails is allowed to 30 permit of ordinary expansion and contraction.

Some changes may be made in the construction and arrangement of the parts of my improved device without departing from the essential features and purposes, and it is 35 my intention to cover by this application any such changes which may be included within the reasonable scope of my claims.

I claim as my invention:

1. A rail joint comprising a pair of rails 40 having the sides of the rail ball cut away adjacent to the ends of the rails, and having a notch in the upper portion of the web

near each end of the rail, a joint member having substantially the form of a rail section with a web portion of less height than 45 the web portion of the rail, said joint member being provided with slots to receive the ends of the ball and web of the adjacent rail ends when said joint member is installed by lowering it from above downwardly upon 50 the ends of the rails, a cradle comprising a plate arranged beneath the rail joint, upwardly extending side members, and upwardly and inwardly projecting lugs at the ends of said side members arranged above 55 the base of said rail joint member, and a pin extended through the central portion of said rail joint member for limiting the longitudinal movement of said cradle.

2. A rail joint comprising a pair of rails 60 having the sides of the rail ball cut away adjacent to the ends of the rails, and having a notch in the upper portion of the web near 65 each end of each rail, a joint member having substantially the form of a rail section with a web portion of less height than the web portion of the rail, said joint member being provided with slots to receive the ends of the ball and web of the adjacent rail ends when said joint member is installed by 70 lowering it from above downwardly upon the ends of the rails, a cradle comprising a plate arranged beneath the rail joint, upwardly extending side members, and upwardly and inwardly projecting lugs at the 75 ends of said side members arranged above the base of said rail joint member, a pin extended through the central portion of said rail joint member for limiting the longitudinal movement of said cradle, the parts 80 being so arranged as to allow longitudinal play of the rails.

Des Moines, Iowa, May 6, 1916.

EDWARD T. LASKEWITZ.
